United States Patent Office

Des. 200,601
Patented Mar. 16, 1965

200,601

SPECTACLE FRAME

Harold A. Meyers, 425 W. Cypress Ave., Glendale, Calif.

Filed Aug. 3, 1964, Ser. No. 81,143

Term of patent 14 years

(Cl. D57—1)

FIG. 1

FIG. 2

FIG. 3

FIG. 4

FIG. 1 is a front elevational view of a spectacle frame, showing my new design;

FIG. 2 is a fragmentary top plan view thereof;

FIG. 3 is a fragmentary top plan view of the temple portion thereof; and

FIG. 4 is a side elevational view thereof.

The dominant features of my design reside in the portions shown in full lines.

I claim:

The ornamental design for a spectacle frame, as shown and described.
